DESIGN FOR A HAIR ORNAMENT

Leo J. Gagnon, Leominster, Mass., assignor to Fosgood Corporation, Leominster, Mass., a corporation of Massachusetts

Application June 8, 1938, Serial No. 77,670

Term of patent 3½ years

To all whom it may concern:

Be it known that I, Leo J. Gagnon, a citizen of the United States and resident of the city of Leominster, in the county of Worcester and State of Massachusetts, have invented a new, original, and ornamental Design for a Hair Ornament, of which the following is a specification, reference being had to the accompanying drawing, forming part thereof, in which:

Fig. 2 is a cross-sectional view taken on the line 2—2 of Figure 1.

Fig. 3 is a rear plan view thereof.

The dominant features of my design reside in the portions shown in full lines.

I claim:

The ornamental design for a hair ornament, substantially as shown and described.

LEO J. GAGNON.
